CLAIM

The ornamental design for a trash bin, as shown and described.

DESCRIPTION

FIG. 1 is a top perspective view of a trash bin showing the new design.

FIG. 2 is a front view thereof.

FIG. 3 is a side view thereof.

FIG. 4 is another side view thereof.

FIG. 5 is a rear view thereof.

FIG. 6 is a top view thereof; and,

FIG. 7 is a bottom view thereof.

The broken lines shown in the figures are for the purpose of illustrating portions of a trash bin and form no part of the claimed design.

The trash bin is shown with a symbolic break in its height. The dot-dash lines depict the symbolic break. The appearance of any portion of the article between the break lines forms no part of the claimed design.
